Primary Examiner — Jae Liang*Assistant Examiner* — Ji Sun Yoon(74) *Attorney, Agent, or Firm* — Howard E. Chung(57) **CLAIM**

The ornamental design for an insulated food carrier, as shown and described.

DESCRIPTION

FIG. 1 is a perspective view of an insulated food carrier, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front and top perspective view thereof, shown in an open condition; and,

FIG. 9 is a front and top view thereof, shown in an open condition.

The broken lines on the sidewall near the zipper areas in FIGS. 1-5 and 8-9 are included to show unclaimed stitches on the insulated food carrier.

The broken lines in the figures illustrate portions of the insulated food carrier that form no part of the claimed design.
